Philip S. McLean,
Inventor

UNITED STATES PATENT OFFICE.

PHILIP S. MCLEAN, OF BLOOMFIELD, NEW JERSEY.

ELECTRICAL ATTACHMENT-PLUG.

1,228,337.

Specification of Letters Patent.

Patented May 29, 1917.

Application filed April 4, 1916. Serial No. 88,790.

To all whom it may concern:

Be it known that I, PHILIP S. MCLEAN, a citizen of the United States of America, residing at Bloomfield, New Jersey, have invented a new and useful Electrical Attachment-Plug, of which the following is a specification.

My invention relates particularly to attachment plugs of the "swivel" type, and the general objects of the invention are to improve, simplify and reduce the cost of devices of this character.

A special object of the invention is to provide a swivel plug whose parts can be readily separated for wiring purposes and in which the parts, when the plug is assembled, will be held positively locked together.

A further object is to provide a plug of good mechanical strength, having high current carrying capacity and in which the current carrying parts are well insulated and properly protected.

In the accomplishment of the foregoing and other objects, I employ an insulating base on which the circuit terminals are mounted and secure the rotating screw shell contact on this base by means of an end contact member mounted on the base, suitable insulation being interposed to prevent a short connection between the end contact and rotatable screw shell.

Another feature of the invention is the making of the end contact readily releasable from its holding position so as to permit easy separation of the two relatively rotatable members of the plug.

Other features of the invention have to do with the details of construction, etc., all of which will appear as the specification proceeds, attention being directed to the accompanying drawings forming part hereof and wherein I have illustrated practical forms the invention may take.

45 In said drawings:

Figure 1 is a vertical sectional view of a plug embodying the invention.

Fig. 2 is another sectional view taken substantially on the plane of the line 2-2, Fig. 1.

Fig. 3 is a view similar to Fig. 1 showing the end contact in "released" position to permit separation of the parts.

Fig. 4 is a drop perspective view of the insulating base member and the several parts carried thereby.

Fig. 5 is a view showing the terminal carrying insulating base member separated from the screw shell.

Fig. 6 is a sectional view similar to Fig. 1 illustrating a slightly different form of the invention wherein the screw-shell-retaining end contact member is held seated in its securing position by a spring instead of a screw such as shown in the first form.

Fig. 7 is another sectional view showing the end contact in this form of construction released to permit separation of the parts.

Fig. 8 is a top plan view of the terminal carrying base.

Fig. 9 is a detached perspective view of the end contact member in this form of construction.

Fig. 10 is a view illustrating the blank from which this end contact may be made.

Fig. 11 is a bottom plan view of the insulating base.

Referring now to the drawings more in detail:

15 designates the insulating base or body 80 of the plug, generally circular in form and provided in the case illustrated, with an outstanding flange 16 at the lower end thereof.

Mounted on this base are the terminals 85 for the two line wires, one of these terminals, in the first form of the invention illustrated, being designated 17, and the other 18, the first being connected by a screw 19 with the center or end contact 20 and the other being provided with a laterally outstanding foot 21 seated in a recess 22 in the flange of the base and providing a contact for engagement by the flange 23 turned in at the lower end of the screw shell contact 24.

The circuit terminal 18 is secured in place in the construction illustrated, by forming it with outstanding lugs 25 engaging in an undercut groove-way 26 formed in the side 100 of the base. These outstanding lugs 25 may be produced by simply punching a hole in the body of the circuit terminal as indicated at 27 so as to spread the metal at this point and produce projecting lugs at the opposite 105 edges of the terminal. It will be seen from this that this circuit terminal may be secured in place by simply dropping it into the upper end of the undercut groove-way. The binding screw 28 of this terminal may engage in a transversely extending seat 29 formed at the back of the undercut groove-

way to prevent accidental disengagement of the circuit terminal.

The other circuit terminal 17 may seat in a socket 30 provided for it in the top of the insulating base and an insulating wall 31 is preferably provided to form an insulating barrier between the two circuit terminals.

The end contact member 20 is of novel construction embodying in addition to the contact making end portion thereof, a shank extension 32 terminating in a laterally projecting lug 33 which makes holding engagement with the flange portion of the screw shell contact, suitable insulating medium being interposed at some point in this line of connection. This insulating medium consists in the present disclosure of a washer or bushing 34 of insulating material lining the lower end portion of the screw shell contact 20 and bearing on the inturned flange 23.

As most clearly shown in Figs. 1 and 3, the shank extension 32 of the end contact is received in a longitudinally extending passage 35 extending upward from the lower end of the base, said passage opening laterally out through the side of the base at a point above the outstanding flange 16, as indicated at 36, to permit the holding lug 33 to project laterally out over the insulating washer in the lower end of the screw shell. In the holding position of the end contact, the holding lug 33 is preferably "backed" up both at the top and at the rear by supporting and bracing walls 37 and 38 so as to prevent the end contact being sprung and the parts separated by force. Further, in the normal position of the parts, the exposed end portion of the end contact seats in a socket 39 in the end of the base shaped to receive it.

In the normal condition of the plug, as indicated in Fig. 1, the center securing screw 19 holds the end contact seated in holding position with the holding lug thereof overlying the insulating shoulder in the lower end of the shell contact. The shell contact is thus rotatably confined to the base. When it is desired to release the plug, it is merely necessary, in this form of the invention, to loosen the holding screw 19 as indicated in Fig. 3, far enough to permit the end contact to drop downward and inward far enough for the holding lug thereon to clear the insulating shoulder in the lower end of the screw shell contact. In this condition the screw shell can be readily slipped off the base for the purpose of wiring or unwiring the plug, repairing or the like. The upper end of the holding screw may be headed over as indicated at 40 to prevent the screw being wholly withdrawn and disengaged from the upper circuit terminal.

The insulating shoulder preferably extends inward past the inner periphery of the inturned flange on the shell, as indicated in Figs. 1, 2 and 3, so as to prevent the pos-

sibility of the holding lug engaging the flange during separation of the parts. Furthermore, the insulating bushing preferably extends up into the screw shell some distance above the holding lug, and the end of the holding lug preferably terminates just short of the inner wall of the insulating lining, as indicated at 41 in Fig. 1, so as to avoid any possibility of the end of the holding lug working through the insulating lining.

The parts of opposite polarity may if desired be further insulated by the provision of an insulating cap 42 resting on top of the insulating base and covering the upper circuit terminal.

The screw shell is provided at its upper outer end with a suitable hand-hold 43 preferably of insulating material, a convenient method of securing the screw shell and hand-hold together being to mold the hand-hold about out-turned flanges or fingers 44 provided at the upper end of the screw shell.

In the second form of the invention illustrated, the end contact 45 is provided with a shank extension 46 and with a holding lug 47 as before, and in addition thereto, is provided with an upstanding stud 48 provided at its upper end with a circuit terminal member 49 with which a binding screw 50 or the like may be engaged. Fig. 10 illustrates how this end contact may be blanked out from a flat strip of metal 51, the stud 48 being formed as an integral member cut therefrom along the dotted lines 52.

The end contact is in this form shown normally seated in its holding position by means of a spring 53 seated in a pocket 54 in the top of the insulating base and engaged beneath the circuit terminal head on the upper end of the stud 48.

With this construction, it will be clear that the parts may be released by simply pulling the end contact out of its seat as indicated in Fig. 7, a thumb nail recess 55 being usually provided to permit the engagement of the thumb nail beneath the end contact for the purpose of thus releasing the parts. This ready separability of the two parts of the plug is of considerable advantage in that the parts can be instantly separated without any prior manipulation of screws or other elements. At the same time it will be noted that in the construction shown, the parts when assembled, are positively locked together and accidental separation of the same is prevented, it being noted that a pull tending to separate the parts is taken up by the rigid supporting wall 37 and 38.

In this form also, I have illustrated how the end contact may, as indicated in Fig. 6, be extended over so as to substantially close up the end of the passage 35 through which the shank 46 of the end contact extends.

The insulating base of the plug is of such

simple construction that it can be readily molded from porcelain or any other suitable insulating material, and as this material is cheaper than metal, I have illustrated in 5 Figs. 6 and 7 how the base may be made comparatively long and the screw shell contact be made relatively short, it being merely necessary to make this screw shell contact long enough to take into the screw shell of 10 the socket which the plug is intended to fit.

What I claim is:

1. An attachment plug comprising an insulating base, circuit terminals on said base, a screw shell rotatable about the base and 15 provided with an inwardly projecting flange, a contact on the base connected with one circuit terminal and engaging with the screw shell contact, an end contact on the base connected with the other circuit terminal provided with a holding lug to overstand the inwardly projecting flange on the screw shell and means for shifting the end contact laterally to carry said holding lug into position overstanding said inwardly projecting 25 flange.

2. An attachment plug comprising an insulating base, circuit terminals on said base, a screw shell contact rotatable about the base and provided with an inwardly projecting flange, a contact on the base connected with one circuit terminal and engaging with the screw shell contact, an end contact on the base electrically connected with the other circuit terminal and provided with a holding lug overstanding the inwardly projecting flange on the screw shell contact to rotatably confine the same to the base and an insulating medium interposed between the 35 end contact and shell contact.

3. An attachment plug comprising an insulating base, circuit terminals on said base, a screw shell contact rotatable about the base and provided with an inwardly projecting flange, a contact on the base connected with 40 one circuit terminal and engaging with the screw shell contact, an end contact movably mounted on the base electrically connected with the other circuit terminal and provided with a holding lug arranged in one position 45 of said end contact to overstand the inwardly projecting flange to hold the screw shell rotatably confined to the base and in another position of said end contact to be clear of the flange to release the screw shell 50 from the base and means for normally maintaining the end contact with the lug thereof in its holding position.

4. An attachment plug comprising an insulating base, circuit terminals on said base, 55 a screw shell contact rotatable about the base and provided with an inwardly projecting flange, a contact on the base connected with one circuit terminal and engaging with the screw shell contact, an end contact 60 releasably seated on the end of the base

electrically connected with the other circuit terminal and provided with a laterally extending lug overlying the flange of the screw shell contact in the seated position of said end contact to thereby rotatably confine said screw shell contact to the base, means for insulating said end contact from the screw shell contact and readily releasable means for normally maintaining the end contact seated in its holding position. 70

5. An attachment plug comprising an insulating base, circuit terminals on said base, a screw shell contact rotatable about the base and provided with an inwardly projecting flange, a contact on the base connected with one circuit terminal and engaging with the screw shell contact, an end contact movably mounted on the base and provided with an outstanding lug arranged in one position of said end contact to hold the 75 screw shell rotatably confined to the base and in another position of the end contact to release the screw shell from the base and means for holding the end contact in its holding position and for releasing it from such holding position, said means providing a means of electrical connection between the end contact and the other circuit terminal. 80

6. An attachment plug comprising an insulating base substantially circular in form 85 and provided with an outstanding flange at the lower end thereof, said base having a recess in one side thereof with undercut walls, a circuit terminal seated in said recess, having portions engaged behind said 90 undercut walls and provided at its lower end with an outstanding foot portion bearing on the flange of the base, a screw shell surrounding said base and provided with an end flange bearing on said angularly 95 outstanding foot portion of the circuit terminal, and readily releasable means for detachably confining the screw shell in position upon the base. 100

7. An attachment plug comprising an insulating base, circuit terminals on said base, a screw shell contact rotatable about the base and provided with an inwardly projecting flange, a contact on the base connected with one circuit terminal and engaging with the 110 screw shell contact, a holding member mounted on the base and laterally shiftable thereon, and means extending longitudinally of the base for shifting said holding member laterally on the base into position 115 overstanding the inwardly projecting flange on the screw shell contact. 120

8. An attachment plug comprising an insulating base, circuit terminals on said base, a screw shell contact rotatable about the 125 base and provided with an inwardly projecting flange, a contact on the base connected with one circuit terminal and engaging with the screw shell contact, a holding member mounted on the base and later- 130

- 4
- ally shiftable thereon, a shoulder for holding said member laterally shifted in position overstanding the flange on the screw shell contact, and a screw extending longitudinally of the base into engagement with the other circuit terminal adapted when tightened to hold the holding member in engagement with the shoulder on the base and in position overstanding the inwardly projecting flange and when loosened to allow the holding member to move into position free of the inwardly projecting flange.
9. An attachment plug comprising an insulating base, circuit terminals on said base, a screw shell contact rotatable about the base and provided with an inwardly projecting flange, a contact on the base connected with one circuit terminal and engaging with the screw shell contact, an end contact on the base electrically connected with the other circuit terminal and provided with a holding lug overstanding the inwardly projecting flange on the screw shell contact to rotatably confine the same to the base and an insulating lining in the screw shell having an inwardly projecting shoulder above the flange thereof adapted to be engaged by
- 5 10 15 20 25
- the holding lug and said holding lug terminating short of the side wall of said insulating lining to thereby prevent wearing of said side wall of the lining.
10. An attachment plug comprising an insulating base, circuit terminals on the upper portion of said base, a screw shell contact rotatable about the base and inclosing said circuit terminals, said screw shell contact having an inwardly projecting flange, an insulating cap applied to said insulating base and covering the circuit terminals thereon to thereby form an insulating barrier between the same and the surrounding screw shell contact, a contact on the base connected with one circuit terminal and engaging with the screw shell contact, an end contact laterally shiftable on the base and having a lug adapted to overstand the inwardly projecting flange on the screw shell contact, a connection between said end contact and the other circuit terminal and an insulating lining in the screw shell contact having a shoulder above the inwardly projecting flange to be engaged by the holding lug.

PHILIP S. McLEAN.
